(57) **CLAIM**

I claim the ornamental design for a fine mesh traveling water screen assembly, as shown and described.

DESCRIPTION

FIG. 1 is a plan view from the top of the fine mesh traveling water screen assembly showing our new design;

FIG. 2 is a plan view from side of screen;

FIG. 3 is a plan view from end of screen;

FIG. 4 is a cross section view of FIG. 1 through 4-4; and,

FIG. 5 is a cross section view of FIG. 1 through 5-5.

The broken line showing is included for the purpose of illustrating portions of the article and forms no part of the claimed design.
